UNITED STATES PATENT OFFICE

EDWARD A. WILLIFORD, OF LAKWOOD, OHIO, ASSIGNOR TO NATIONAL CARRON CO., INC., A CORPORATION OF NEW YORK

BRUSH

Application filed May 21, 1928. Serial No. 279,589.

My invention relates to means for connecting electrical conductors to brush members.

The carbon and graphite brushes ordinarily used in connection with rotating parts of electrical machines are composed of a comparatively fragile and friable material as compared with the metal conductors or leads to which the brushes are attached. In order to form a satisfactory conducting path between such brushes and the metal conductors, a high pressure is necessary. This pressure is sufficient to cause a stretching of the metal parts of the clamping devices and a slight flowing of the clamped-on metal of the conductor. These changes require a re-adjustment of the metal or of the strands of the conductor in order to maintain a good conducting path. The brushes are subjected to considerable variations in temperature which cause an excessive pressure on the conductor eyelets at certain times and an insufficient pressure at other times. The vibration to which the brushes are subjected in service also causes the friable brush material in contact with the conductor eyelets to wear away. These things result in defective electrically conductive paths between the brush and the connector and excessive heating and destruction of the brushes result.

Heretofore the conductors have been fastened to the brushes with bolts or rivets and no provision has been made to compensate for the changes in volume of the connected parts. Resilient connections have also been proposed but there has been no means in such connecting members to provide for a sufficient re-adjustment of the parts and a sufficient and constant high pressure to prevent faulty conduction and excessive heating at the points of contact of the brush and conductor.

I have made a device which provides a sufficient pressure on the brush to give a good electrical contact and which provides compensating means to counteract the expansion, contraction, wear and flow of the materials of the contact members.

My invention will be more fully under-

stood by referring to the drawings, constituting a part thereof, in which,

Figure 1 is a side elevational view of a brush member having a cabled conductor connected thereto.

Figure 2 is a cross-sectional view of the brush taken along the line II-II of Figure 1.

Figure 3 is a cross-sectional view of a brush similar to Figure 2 illustrating a modification of my invention; and

Figure 4 is a cross-sectional view of a brush similar to Figure 2 illustrating another modification of my invention.

Referring to Figures 1 and 2 a brush 1 is provided with a countersunk bore through which the bolt 2 is passed. The walls of the countersunk portions at the ends of the bore are parallel to the axis of the bore and provide spaces in which the conducting members are assembled. The countersunk portions are preferably of sufficient depth to permit the ends of the bolt to terminate just below the surface of the brush and a channeled opening 3 is preferably provided in the brush material so that the cabled leads 4 can be conveniently introduced into the countersunk portions. Eyelets 5 which are formed in the leads 4 are placed in the countersunk bores next to the brush and flat washers 6 are mounted on the eyelets. The washers may be made of metal or of any other deformable material so that they will spring slightly when they are depressed and they are made to conform to the walls of the bores so that they will act as pistons and confine the conductor material in the bores. The bolt 2 is passed through the brush and eyelets. On one end of the bolt the eyelet and washer are held by the head 7 and on the other end they are held by curved resilient washers 8 and 9 and a nut 10.

The resilient washers 8 and 9 which are preferably cup-shaped or dished are mounted on the bolt 2 with their concave surfaces facing each other so that the contact between the washers 8 and 6 will be a small circular area around the bolt 2 near the surface of the bolt. For the purpose of illustrating the invention the curvature of 100

the washers 8 and 9 has been exaggerated but in practice the nut is screwed down so that the surfaces of the washers are more nearly parallel. The nut 10 is screwed 5 down on the washer 9 with sufficient pressure to form a good contact between the brush material and the cabled conductor eyelets at the ends of the bolt. One end of the bolt may be upset to prevent the bolt from 10 unscrewing.

When the washers 8 and 9 are compressed, a pivotal contact member is formed between the washers and the members bearing thereon. There tends to be a concentration of 15 stresses in the area of the washers 6 near the surfaces of the bolt 2 and in a similar area in the nut. The stresses in the nut are transmitted to the bolt and to the opposite end thereof whereby contact between the 20 brush and the eyelet underneath the bolt head is maintained. The concentration of stresses in the washer 6 tends to compress the central portion of the washer and to distribute the stresses in the eyelet material 25 from a central peripheral area near the bolt. The washers 6 operate as pistons in the countersunk portions of the bore and confine the deformed material of the conductor eyelet within the bore. This action is effective in 30 compressing the eyelet material into close contact with the brush and a perfect conducting path is thereby formed between the conductor and the brush. A change of volume of the eyelet material which makes 35 necessary a re-adjustment of the bolt 2 and washers 6 is effected by the resilient washers which provide a pivotal connection between the bolt and the confined eyelet material and a continuous constant application of the necessary pressure to bring about the re-adjustment. Thus an effective redistribution of 40 stresses is facilitated by this arrangement and a perfect conducting path is maintained.

Although the modification shown in Figures 1 and 2 is preferred for most purposes, I may employ the modifications shown in Figures 3 and 4. In Figure 3, the curved washers 15 and 16 are mounted on opposite ends of the bolt with their convex surfaces 45 contacting with the washers 6. The concave surface of the washers face outwardly. The washer 15 bears against the bolt head 7 and the washer 16 bears against a flat washer 17. The structure is assembled by screwing 50 down a nut 10 on the washer 17. In this modification, there is a resilient compensating element directly connected with each end of the bolt. The oppositely disposed washers compensate for the changes 55 in volume of the elements of the connector and they exert a wedging action on the material of the eyelets 5 in the countersunk bore through the washers 6.

I have found that the pressure need not 60 necessarily be concentrated in the flat wash-

ers 6 in their central areas. It may be applied to an outer area of the washers 6. In Figure 4, I have shown two washers 18 opposed to each other on the ends of the bolt. The washers 18 are mounted on the washers 6 so that the area of concentrated stresses is in an area of the washers 6 near their margins and the parts are fastened together by forming rivet heads 19 at the ends of the bolt. This arrangement likewise provides 70 a pivotal connection between the connector and the washer 6 and means for compensating for the changes in the volume of the materials. The wedging of the material of the eyelets 5 is also provided for but in this 75 modification the wedging force is applied at the outer periphery of the washer and tends to force the material toward the central bolt.

Still other modifications of my device may 80 be made without departing from the spirit of my invention. The double cup washer shown in Figure 1 may be used on both ends of the bolt instead of the single washers shown in Figures 3 and 4, tubular rivets may 85 be used instead of solid rivets, appropriately shaped springs may be used instead of the cupped washers and other combinations which have not been specifically described 90 may be used. Therefore it is to be understood that I do not wish to limit my invention except by the prior art and by the invention as defined in the annexed claims.

I claim as my invention:

1. The combination with a brush having 100 an elongated bore therethrough and an enlarged portion at the end of the bore having walls parallel to the bore, of means for connecting a conductor which comprises a bolt member in the bore, a conductor member 105 around the bolt in the enlarged portion of the bore, a perforated flat member adapted to confine the conductor material in said enlarged portion of the bore and a cup-shaped 110 spring element having a circular bearing surface on a portion only of the contacting surface of the washer whereby the washer tends to be deformed and to wedge the confined conductor material when the spring element is compressed.

2. The combination with a brush having a transverse bore therethrough and an enlarged depression at the ends having walls parallel to the axis of the bore, of means for connecting a conductor which comprises a 115 bolt member in the bore, a conductor member mounted thereon in said depression, a washer member adapted to operate as a piston in the depression and to compress the material of the conductor against the walls 120 of the depression, a cup-shaped spring member having a circular bearing surface on a portion only of the contacting surface of the washer, and means cooperating with said bolt to compress said cup-shaped members 125 130

whereby a resilient pivotal connection is formed between said bolt and conductor members.

3. The combination with a brush having a transverse bore and an enlarged depression at the ends having walls parallel to the axis of the bore, of means for connecting a conductor which comprises a bolt having a head on one end and threaded means on the other end, conductor members mounted on the bolt in the depressions, washers on said members adapted to operate as pistons in the depressions and to compress the material of the conductor members against the walls of the depressions, a pair of cup-shaped spring members having their concave surfaces facing each other mounted between said threaded means and one of said washers whereby a compensating pivotal connection is formed between said bolt and conductor members.

4. In a current-carrying brush having a hole therethrough, a lead, means for attaching said lead to said brush comprising a clamping bolt within said hole, said lead having a terminal engaging one end of said bolt and disposed adjacent to the side of said brush, a clamping nut for fixing said terminal against the side of the brush and resilient means carried by the bolt for preventing stretching thereof by reason of thermal expansion of the brush, said resilient means being so designed as to provide resiliency substantially equal to the elastic tensile limit of said clamping bolt.

5. In a current-carrying brush having a hole therethrough, a lead, means for attaching said lead to said brush comprising a clamping bolt within said hole, said lead having a terminal engaging said bolt and disposed adjacent to the side of said brush, a clamping nut for fixing said terminal against the side of the brush and a cup-shaped spring washer carried by the bolt and capable of withstanding pressure substantially equal to the elastic limit of said bolt, said washer being capable of sufficient deflection to offset any tendency of said bolt to stretch.

6. In a current-carrying brush having a hole therethrough, a lead, means for attaching said lead to said brush comprising a clamping bolt within said hole, said lead having a terminal engaging one end of said bolt and disposed adjacent to the side of said brush, a clamping nut for fixing said terminal against the side of the brush and a spring washer carried by the bolt for preventing stretching thereof by reason of thermal expansion of the brush.

7. In a current-carrying brush having a hole therethrough, a lead, means for attaching said lead to said brush comprising a clamping bolt within said hole, said lead having a terminal engaging one end of said bolt and disposed adjacent to the side of

said brush, a clamping nut for fixing said terminal against the side of the brush and a spring cup-shaped washer carried by the bolt for preventing stretching thereof by reason of thermal expansion of the brush.

In testimony whereof, I affix my signature.

EDWARD A. WILLIFORD.
